ABSTRACT

A lock mechanism mounted in a casing including a bolt member slidably mounted in the casing for movement between lock and unlock positions. A plurality of latch levers and at least one master lever are pivotally mounted in the casing by means of a pivot pin. The latch levers engage and restrain movement of the bolt member when biased in one direction. A spring means is provided for biasing the latch levers and master lever in one direction. The spring means is of novel construction having a frame portion and a plurality of spring arms formed integrally therewith. The spring arms are arranged in two banks with the spring arms of one bank extending towards and in staggered relationship with the spring arms of the other bank. A key guide member is rotatably mounted in the casing to receive a key which when rotated will pivot the latch levers (or the master lever) against the bias of the spring arms of the spring member to thereby move the latch levers out of restraining engagement with the bolt member. The pivot pin is journaled in opposite walls of the lock casing and the master lever is fixedly secured to the pivot pin.

LOCK MECHANISM

BACKGROUND OF THE INVENTION

I. Field of the Invention

This invention relates to a lock mechanism and more particularly to a spring member of improved design for biasing the latch levers of the lock mechanism.

II. Description of the Prior Art

The conventional approach in lock mechanisms of the type involved herein is to use a separate spring element for each latch lever. Such an arrangement is more costly to manufacture because of assembly difficulties. The only one-piece type spring member known to applicant employs a plurality of spring arms all of which extend in a single direction. Such construction makes it difficult, if not impossible, to provide a separate and independent biasing force to each of the latch levers. The primary object of this invention is to provide a lock mechanism which is economical to manufacture and provides a smooth and precise operation.

SUMMARY OF THE INVENTION

A lock mechanism mounted in a lock casing including a bolt member slidably mounted in the casing and a plurality of latch levers pivotally mounted in the casing and adapted to restrain movement of the bolt member when biased in one direction. A spring means is provided for biasing the latch levers in said one direction. The spring means is comprised of a spring member having a frame portion and a plurality of spring arms formed integrally therewith. The spring arms are arranged in two banks with the spring arms of one bank extending towards and in staggered relationship with the spring arms of the other bank so that adjacent latch levers are separately and independently biased by alternately staggered spring arms.

DESCRIPTION OF THE DRAWINGS

FIG. 1 is a perspective view of a flat key lock which embodies the structure of the present invention;

FIG. 2 is an enlarged front view of the lock shown in FIG. 1 with the cover plate removed;

FIG. 3 is a sectional view taken along line 3—3 of FIG. 1 but with a key inserted and rotated one-half the way (90 degrees) through its normal operational travel;

FIG. 4 is an enlarged perspective view of the novel one-piece spring member for the lock; and

FIG. 5 is an enlarged perspective view of the master lever used in the lock.

DESCRIPTION OF THE PREFERRED EMBODIMENT

Referring to the drawings in detail, the lock mechanism of the present invention is mounted in a metal case 10 having a cover plate 12 and a pair of apertured attachment flanges 14, 14. Case 10 also includes side-walls 16, 18, 20, 22 and a rear wall 24.

The lock mechanism mounted in case 10 includes a bolt member 26 mounted for sliding movement adjacent the rear wall 24 of the case and is comprised of a plate portion 28, a locking nose portion 30 and a locking bar or lug 32 fastened to plate portion 28 and extending at right angles to the plane of plate portion 28. Plate portion 28 is also provided with a key actuation slot 31, as shown in FIG. 2.

The lock mechanism further includes a plurality of latch members 34a, 34b, 34c, 34d, 34e and 34f, and a

master lever 36. The latch and master levers are mounted in a stacked relationship as best shown in FIG. 3.

Master lever 36 (FIG. 5) is mounted with a pressed fit on one end of a pivot pin 38 and latch levers 34a-34f are freely pivotally mounted on the remaining portion of pin 38. The entire sub-assembly of latch levers, master lever and pivot pin is mounted in the case with the opposite ends 40, 40 of pin 38 journaled in openings 42, 42 in cover plate 12 and rear wall 24 of lock case 10.

A spring member 44 of novel design is provided to bias the latch and master levers (downwardly as shown in FIGS. 2 and 3) to their "lock" or "unlock" positions. As best shown in FIG. 4, spring member 44 is of one-piece construction comprising a frame portion 46 having integral end extensions 47, 47 providing an essentially C-shape configuration and a plurality of curved spring arms 48a, 48b, 48c, 48d, 48e, 48f and 48g. Spring arms 48a, 48c, 48e and 48g, which form one bank of spring arms, extend from one end 47 of frame portion 46, and spring arms 48b, 48d and 48f, which form a second bank of spring arms, extend from the other end 47 of frame portion 46. The spring arms of the two banks are staggered with respect to each other, i.e., they extend towards each other with the center lines of one bank of spring arms extending between the spring arms of the other bank and vice versa. The free ends 49 of each spring arm are of reduced width to make sure that each spring arm will make contact with only a single lever.

It is important to note that in fabricating spring member 44 the metal between adjacent spring arms 48a-g is removed, leaving spaces 51 between adjacent spring arms. Such removal of metal between adjacent spring arms reduces the amount of undesirable stresses left in the spring arms due to the rupture of the metal in the manufacturing process as compared to a spring construction wherein the spring arms are formed by slitting or drawing the material without removal of any metal. In the latter construction it is necessary to heat treat the material to stress relieve the spring. No such heat treatment operation is required in the manufacture of the spring member of the present invention.

As best shown in FIGS. 3 and 4, spring member 44 is mounted in case 10 with the flat frame portion 46 and extensions 47 positioned flush against top wall 22 of the case with the spring arms thereon extending downwardly into contact with surfaces 50 and 52 of the master and latch levers. With the specially designed spring member 44 of the present invention, each latch and master lever will be independently biased to its lock (or unlock position) by a single spring arm. More specifically, spring arm 48a is in biasing contact with lever 34a, spring arm 48b is in biasing contact with the next adjacent lever 34b, spring arm 48c is in biasing contact with next adjacent lever 34c, spring arm 48d is in biasing contact with next adjacent lever 34d, spring arm 48e is in biasing contact with next adjacent lever 34e, spring arm 48f is in biasing contact with next adjacent lever 34f, and spring arm 48g is in biasing contact with master lever 36.

In the preferred embodiment spring member 44 is made of phosphorus bronze. Because of its structural configuration it lends itself to mass production techniques of manufacture such as a progressive stamping-forming process.

Referring again to master lever 36 and latch levers 34a-34f, master lever has a flat top surface 50 and latch levers have flat top surfaces 52 for uniform biasing engagement with the spring arms 48a-48g. Master lever 36 has a cam surface 54 for actuation by a corresponding actuating surface on a master key (not shown). The master lever 36 also has an actuator bar 58 which extends through aligned openings 60 in the latch members as best shown in FIG. 2. Latch members 34a-34f have cam surfaces 62 of varying configurations, each adapted for actuating contact with a corresponding actuating surface 64 on the shank of key 66 as best shown in FIG. 3. The bolt member 26 is actuated by actuating surface 65 at the end of key 66 which is adapted to engage slot 31 in plate portion 28 as will be described in detail hereinafter. Each of such latch members is also provided with a retaining slot 68 and a projecting lug 70 which cooperate with locking bar 32 on bolt member 26 to retain the bolt member in either "lock" or "unlock" position.

A key guide member 72 is rotatably journaled in a hollow boss 74 on cover plate 12 and an opening 76 in rear casing wall 24. As best shown in FIG. 1, the end of locking bar 32 extends into a guide slot 78 in cover plate 12 to provide a further guide means for the sliding movement of bolt member 26.

OPERATION

FIGS. 1 and 2 show the lock mechanism in "unlock" position. To actuate the lock from "unlock" to "lock" position, key 66 is inserted into key guide member 72 and then rotated 180° counterclockwise. During the first 90° of rotation, actuating surfaces 64 on key 66 will engage cam surfaces 62 on latch levers 34a-34f causing said levers to be pivoted upwardly against the bias of spring arms 48a-48f of spring member 44 from the position shown in FIG. 2 to the position shown in FIG. 3. Such upward pivotal movement of the latch levers to their release position will cause projecting lugs 70 thereon to move up and out of the travel path of locking lug 32 on bolt member 26.

Toward the latter part of the first 90° of key rotation and during the second 90 degrees of key rotation actuating surface 65 at the end of key 66 will become engaged in slot 31 in the bolt member 26. With the latch levers actuated to release position, the bolt member 26 will be free to slide (to the left as viewed in FIG. 2) by the action of key surface 65 in slot 31. The rotation of the key will thus slide bolt 26 to its "lock" position shown in dotted lines in FIG. 2. As the key is rotated to its fully "lock" position, locking bar 32 will move out from under projections 70 on the latch levers, to thus allow such latch levers to pivot back to their original position under the bias of spring arms 48a-48f. The bolt member 26 will be retained in its "lock" position by projections 70 on latch levers 34a-34f, which as explained above will snap back behind locking bar 32 as the key is rotated to its fully "lock" position. To actuate the lock mechanism from "lock" to "unlock" position, the key is rotated 180° clockwise. During such rotation the latch levers will again be actuated upwardly to their release position to thus allow surface 65 on the key to slide bolt 26 back to its "unlock" position as shown in FIG. 2.

When a master key is employed to actuate the lock, such key (not shown) is provided with an actuating surface adapted for actuating engagement with surface 54

on master lever 36. Actuation of master lever 36 against the bias of spring 48g will cause actuator bar 58 thereon to engage and actuate latch levers 34a-34f to release position to thus permit actuation of the bolt member 26.

It will be appreciated from the foregoing that by the use of a spring member 44 having oppositely extending staggered spring arms, each lever will be separately and independently spring loaded with an equal biasing force exerted on each lever. A smoother more precise operation results, making it more difficult to actuate the lock other than by its corresponding pass key. As indicated previously, the above noted desirable biasing action is accomplished with a one-piece spring member which can be fabricated by use of mass production manufacturing techniques (requiring no heat treatment to remove undesirable stresses) and which can be readily assembled with the other parts of the lock mechanism. Finally, it will also be appreciated that by 10 staking master lever 36 to pivot pin 38 and then in turn journaling the pivot pin in the lock case, the master lever will be firmly supported for pivotal movement in the lock case to thereby further enhance the precise operation referred to above.

We claim:

1. A lock mechanism mounted in a lock casing comprising:

a bolt member slidably mounted in the lock casing; a plurality of latch levers pivotally mounted in the casing and adapted to restrain movement of said bolt member when biased in one direction; spring means for biasing said latch levers in said one direction, said spring means comprising a spring member having a frame portion, a plurality of spring arms formed integrally therewith, said spring arms arranged in two banks with the spring arms of one bank extending towards and in staggered relationship with the spring arms of the other bank.

2. A lock mechanism according to claim 1 in which each of said latch levers is separately and independently biased by a single spring arm of said spring member.

3. A lock mechanism according to claim 1 in which said latch levers are arranged in a stacked relationship with adjacent latch levers separately and independently biased by alternately staggered spring arms of said spring member.

4. A lock mechanism according to claim 1 in which said frame portion of said spring member is positioned in such contact with one wall of the lock casing and said spring arms curving outwardly from the plane of said frame portion into contact with said latch levers.

5. A lock mechanism according to claim 1 in which said frame portion of said spring member has a pair of end extensions to provide an essentially C-shaped configuration with said spring arms of said spring member extending towards each other from said end extensions.

6. A lock mechanism according to claim 5 in which the free ends of said spring arms are of a reduced width.

7. A lock mechanism according to claim 1 in which there are spaces between adjacent spring arms of each bank of spring arms of said spring means.

8. A lock mechanism mounted in a lock casing comprising:

a bolt member slidably mounted in the lock casing and adapted for movement between lock and unlock positions;

a plurality of latch levers and at least one master lever pivotally mounted in the casing by means of a pivot pin, said latch levers adapted to restrain movement of said bolt member when biased in one direction;

spring means for biasing said latch levers and master lever in said one direction, said spring means comprising a spring member having a frame portion and a plurality of spring arms formed integrally therewith, said spring arms arranged in two banks with the spring arms of one bank extending towards and in staggered relationship with the spring arms of the other bank; and

a key guide member rotatably mounted in said casing and adapted to receive a key which when rotated will pivot said latch levers against the bias of said spring means to thereby move said latch levers out of restraining relationship with said bolt member.

9. A lock mechanism according to claim 8 in which said pivot pin is journaled in opposite walls of said lock casing and said master lever is fixedly secured to said pivot pin.

10. A lock mechanism according to claim 8 in which each of said latch levers is separately and indepen-

dently biased by a single spring arm of said spring member.

11. A lock mechanism according to claim 8 in which said latch levers are arranged in a stacked relationship with adjacent latch levers separately and independently biased by alternately staggered spring arms of said spring member.

12. A lock mechanism according to claim 8 in which said frame portion of said spring member is positioned in such contact with one wall of the lock casing and said spring arms curving outwardly from the plane of said frame portion into contact with said latch levers.

13. A lock mechanism according to claim 8 in which said frame portion of said spring member has a pair of end extensions to provide an essentially C-shaped configuration with said spring arms of said spring member extending towards each other from said end extensions.

14. A lock mechanism according to claim 13 in which the free ends of said spring arms are of a reduced width.

15. A lock mechanism according to claim 8 in which there are spaces between adjacent spring arms of each bank of spring arms of said spring means.
